(57) **CLAIM**

The ornamental design for binoculars as shown and described.

DESCRIPTION

FIG. 1 is a front, top and right side perspective view of binoculars, showing my new design;
FIG. 2 is a front view thereof;
FIG. 3 is a rear view thereof;
FIG. 4 is a top view thereof;
FIG. 5 is a bottom view thereof;
FIG. 6 is a left side view thereof;
FIG. 7 is a right side view thereof;
FIG. 8 is a front, top and right side perspective view thereof in a closed position;
FIG. 9 is a front view thereof;
FIG. 10 is a rear view thereof;
FIG. 11 is a top view thereof;
FIG. 12 is a bottom view thereof;
FIG. 13 is a left side view thereof; and,
FIG. 14 is a right side view thereof.

The features shown in broken lines in FIGS. 3, 5, 10 and 12 depict environmental structure and form no part of the claimed design.
